UNITED STATES PATENT OFFICE.

GEORGE B. KEPLINGER, OF CHICAGO, ILLINOIS.

MARKING AND SHADING PEN.

1,254,701.

Specification of Letters Patent. Patented Jan. 29, 1918.

Application filed April 12, 1916. Serial No. 90,675.

To all whom it may concern:

Be it known that I, GEORGE B. KEPLINGER, a citizen of the United States, residing at Chicago, in the county of Cook and State of Illinois, have invented certain new and useful Improvements in Marking and Shading Pens, of which the following is a specification.

This invention relates to marking and shading pens and has as one of its objects to provide a pen of this class which will be adapted for the employment of ordinary writing fluid or heavier shading inks either separately or simultaneously, and which will be capable of being used for a considerable length of time without requiring to be refilled.

Another aim of the invention is to provide a pen of this class embodying a reservoir which is of transparent material enabling the user of the pen to readily ascertain at all times the quantity of ink contained within the said reservoir so that before applying the pen where a mark or figure of considerable length or extent in other directions is to be made, he may determine whether or not there is sufficient ink contained within the reservoir to enable him to actually complete the line or figure.

Another aim of the invention is to provide a pen of this class embodying an ink reservoir which pen will be so constructed that it may be laid down in any position without likelihood of the ink being spilled and may be in use, tilted to any angle without such loss of ink occurring.

In one embodiment of the invention the reservoir of the pen is divided into a number of ink compartments each of which may contain an ink of a color different from that contained within any of the other compartments so that by a single stroke of the pen a broad line or a series of lines comprising different colors may be drawn, thus enabling the figure or design to be executed in a more symmetrical manner than would be possible if each line of a different color were required to be separately drawn.

It is a further object of the invention to so form the marking edge in one embodiment of the invention that the colors from the several ink compartments or chambers may be blended.

In the accompanying drawings:

Figure 1 is a perspective view of one form

of marking pen embodying the present invention.

Fig. 2 is a vertical longitudinal sectional view therethrough.

Fig. 3 is a horizontal sectional view on the line 3—3 of Fig. 2.

Fig. 4 is a front elevation illustrating a modified form of pen.

Fig. 5 is a similar view illustrating a still further modification of the invention.

Fig. 6 is a fragmentary plan view illustrating another modification.

Fig. 7 is a view in elevation of the filler employed in filling the reservoir of the pen.

Fig. 8 is a detail vertical sectional view through the lower end of the filler tube.

Fig. 9 is a bottom end view of the pen shown in Figs. 1 and 2 of the drawing.

In the drawings the reference numeral 1 indicates in general the reservoir of the pen and 2 a tubular socket which is carried by the back of the reservoir and receives one end of the staff of the pen which is indicated by the numeral 3. As before stated, the reservoir is formed from transparent material and preferably from sheet celluloid of a suitable thickness, the material being molded upon hot dies to the required shape. In all forms of the invention the reservoir is preferably substantially of ovate-acuminate shape in cross section, the broader side of the reservoir constituting the back thereof and supporting the socket 2, and the apex or narrow end of the body constituting the marking edge. The front of the reservoir is indicated by the numeral 4 and the rear side thereof by the numeral 5, the end walls being indicated by the numeral 6 and being concavo convex with their convex sides presented outwardly, as clearly shown in Figs. 3, 4, 5 and 6 of the drawings. The front and rear walls 4 and 5 of the reservoir are preferably formed by molding a sheet of the material from which the reservoir is formed, upon a die of the proper shape so that the opposite edges of the sheet will be brought together in overlapped relation. A number of small wires are then disposed between the overlapped edges of the sheet and these edges are pressed together and subjected at the same time to heat whereby they will become united to each other. The wires are then withdrawn and as a result capillary ducts 7 are formed in the marking edge of the reservoir and these ducts open at their 110

 lower ends at the said edge and at their upper ends communicate with the interior of the reservoir. The reservoir may comprise a single chamber or compartment or it may 5 be divided by one or more partitions 8 into a number of ink chambers or compartments 9 and it will be understood that these partitions are preferably of the same material as the walls of the reservoir so that the quantity 10 of ink contained in each chamber or compartment may be readily noted. In that form of the invention shown in Figs. 1 to 3 inclusive of the drawings, the marking edge of the device, which edge is indicated 15 specifically by the numeral 10, is unbroken and as a consequence ink flowing through the capillary ducts 7 to the said edge will be distributed along the entire length of the edge and the figure drawn will be in a solid 20 color or colors. As before stated, the reservoir 1 may comprise a single chamber or a plurality of chambers and in the latter instance each chamber may be filled with an ink of a color different from that contained 25 in the next adjacent or any other one of the said chambers, the ink being independently fed from the respective chambers through the capillary ducts and on to the surface over which the marking edge is passed. In 30 order that the reservoir may be conveniently filled with ink, the reservoir is provided in its front wall with a filling opening 11 of small size and tapered and where the reservoir embodies a single ink chamber but a 35 single one of these filling openings will be provided. However, where the reservoir comprises a number of ink chambers one of the openings will be provided for each chamber as will be readily understood. In a like 40 manner the front wall 4 of the reservoir is provided with one or more vent openings 12 located at the top of said wall. The manner of filling the chamber or chambers 45 of the reservoir will be presently more fully described.

In that form of the invention shown in Fig. 4 of the drawings, the marking edge of the reservoir is indicated by the numeral 13 and this edge is provided at intervals 50 with slits 14 extending a short distance into the said edge portion and dividing the same into a number of marking points indicated by the numeral 15. The capillary ducts in the marking edge of the pen in this form of 55 the invention may be so arranged that one or several of the ducts will extend through a single one of the points 15, it being understood that where, for example, two capillary ducts extend through a single marking 60 point, as indicated at 16, a broader line will be drawn than where a single duct extends through a single one of the said points. It will further be understood that in the use of a pen of this form a plurality of lines 65 will be drawn upon the surface over which

the marking edge is moved and that the distance between the said lines will be uniform in all directions of movement of the pen over the said surface.

In that form of the invention shown in Fig. 6 of the drawings the ink ducts are indicated by the numeral 17 and instead of being capillary are relatively broad or more nearly in the nature of narrow slots so that where these ducts 17 are formed in an unbroken marking edge the ink will be supplied more readily than in the case of the capillary ducts 7 and where the said ducts 17 are formed in separate marking points, lines of different widths may be drawn.

In order that the reservoir may be conveniently supplied with ink, a filling device such as shown in Figs. 7 and 8 is preferably employed and this device includes a tube 18 which is preferably of glass and which is provided at its upper end with a rubber cap 19 resembling the cap of an ordinary medicine dropper or fountain pen filler. The lower end of the tube is contracted as indicated at 20 and has embedded in it a small tube 21 which projects beyond the end of the portion 20 and is of a diameter to fit within the filling opening 11 in the wall of the reservoir. After ink has been drawn into the tube 18 by compression and release of the bulb 19, the projecting end of the tube 21 is inserted into the opening 11 in the wall of the reservoir or chamber which it is desired to fill with ink and the bulb 19 is then compressed so as to discharge the ink from the tube 18 into the said reservoir or chamber, air escaping from the reservoir or chamber through the vent opening 12. By reference to Figs. 7 and 8 of the drawings it will be observed that the lower end of the tube 21 is slightly tapered so that the same may fit snugly within the tapered opening 11 when the filler is employed in introducing ink into the pen.

In that form of the invention shown in Fig. 5 of the drawings, the lower or marking edge of the pen is indicated by the numeral 10^a and in this form of the invention the body of the pen is divided interiorly into three ink compartments, one indicated by the numeral 9^a, another by the numeral 9^b and the third by the numeral 9^c, the marking edge 10^a being interrupted at intervals by notches cut therein and indicated by the numerals 14^a, 14^b, 14^c, and 14^d. It will be observed by reference to the said Fig. 5 that ink of the color contained within the compartment 9^a will flow to the marking edge through all of the ducts located to the right of the notch 14^a and that ink will also flow from this reservoir through the duct immediately to the left of the said notch 14^a to that portion of the marking edge which is located between the notches 14^a and 14^b, this portion of the marking edge being further

supplied with ink of another color from the ink compartment 9^b and these colors being blended. It will also be observed that ink will be supplied to that portion of the marking edge between the notches 14^b and 14^c from the compartment 9^b and to the said marking edge between the notches 14^c and 14^d from the ink compartment 9^c. Also ink will be supplied from the compartment 9^c to the portion of the marking edge at the left of the notch 14^d. Thus, in the specific instance illustrated in this figure, when the pen is drawn over the paper to be marked there will be marked upon the paper a relatively broad line of the color of the ink in the compartment 9^a, a relatively broad line of the blended colors of the inks contained in the compartments 9^a and 9^b, a slightly narrower line of ink of the color contained in the compartment 9^b, a similar line of ink of a color of the ink contained in the compartment 9^c and finally a narrower line of ink of the color contained in the compartment 9^c. This figure, however, is to be taken only as illustrative of one of the many arrangements which may be provided, depending upon the results desired to be obtained.

Having thus described the invention, what is claimed as new is:

- 30 1. In a marking device of the class described, a reservoir divided into a plurality of ink compartments and provided with ink ducts communicating with the interior of the compartments and with the marking edge of the reservoir, the said marking edge being divided into a plurality of marking lengths, one of said lengths containing ducts leading from a plurality of said ink compartments.
2. In a marking device of the class described, a reservoir divided into a plurality of ink compartments and having a marking edge formed with ink ducts, and having an unbroken portion, the ink ducts in the unbroken portion of the length of said edge communicating with a plurality of said compartments.

3. In a marking device of the class described, a reservoir having a marking edge, the said edge being formed with a notch dividing the same into separate marking lengths, and the said edge being formed with ink ducts opening through the said separate lengths and communicating with the interior of the reservoir.

4. In a marking device of the class described, an inclosed reservoir of celluloid or like material, ovate-acuminate in shape, the lower portions of the walls of said reservoir being integrally united to provide a rigid marking edge having a row of capillary ink ducts located relatively close together and opening at their lower ends through the said edge and at their upper ends communicating with the interior of the reservoir.

5. In a marking device of the class described, an inclosed reservoir of celluloid or like material, ovate-acuminate in shape and divided into a plurality of ink compartments each having a vent opening and a filling opening, the lower portions of the compartment walls being united integrally to provide an inflexible marking edge having ink ducts therein, each communicating with the interior of an ink compartment, the lower ends of the ducts opening through the said marking edge and being relatively closely spaced.

6. In a marking device of the class described, an inclosed reservoir of celluloid or like material, ovate-acuminate in shape, the lower portions of the walls of said reservoir being integrally united to provide a rigid marking edge having a row of capillary ink ducts located relatively close together and opening at their lower ends through the said edge and at their upper ends communicating with the interior of the reservoir, said reservoir having a vent opening and a capillary filling opening.

In testimony whereof I affix my signature.
GEORGE B. KEPLINGER. [L. S.]
